UNITED STATES PATENT OFFICE.

ORR C. TRASK, OF TORONTO, ONTARIO, CANADA.

STEAM-PROPELLED VEHICLE.

Application filed April 20, 1923. Serial No. 633,563.

To all whom it may concern:

Be it known that I, ORR C. TRASK, a citizen of the United States, residing at Toronto, Ontario, Canada, have invented certain new and useful Improvements in Steam-Propelled Vehicles, of which the following is a specification, reference being had to the accompanying drawings.

In the operation of automobiles, designed to be propelled by steam forces, it is customary to provide a boiler under the hood of the automobile with burners thereunder for heating the water contained in the boiler and thus generating the steam by which the vehicle is propelled. It sometimes happens that the burners so placed beneath the boiler fail to function properly or are left open so that gases gather in the exhaust chambers of the boiler and should the operator attempt to ignite the burner while these gases are present, an explosion is very probable.

It is the prime object of my invention to provide means for quickly and positively removing these gases from the exhaust chambers so as to dispense with the possibility of an explosion when the burner is ignited and live gases are contained in the exhaust chamber.

It is a further object of my invention to provide such a device of cheap and simple construction and which may be easily assembled and used.

It is a further object of my invention to provide means for assisting in the condensation of the water in the radiator of the automobile which means are used in conjunction with the means for removing gases from the exhaust chamber of the boiler.

With these and other objects in view, my invention consists in the arrangement, combination and construction of the various parts of my improved device as described in my specification, claimed in my claims and shown in the accompanying drawings in which:

Fig. 1 is a plan view of an automobile with certain parts thereof cut away and showing my improved device mounted thereon.

Fig. 2 is a detailed view showing the swinging doors mounted on the boiler and used in removing gases therefrom.

Fig. 3 is a detailed view showing certain features of the means for operating said doors.

Fig. 4 is a further detail showing means for operating the said doors.

Fig. 5 is an elevation of the front end of an automobile with the hood thereof removed and showing the boiler contained therein in section.

Fig. 6 is a diagrammatic view of the electrical wiring used in my improved device.

Fig. 7 is a detailed view showing an electrical connection made by the operation of certain parts of my improved device.

I have shown my improved device mounted upon a conventional automobile having frame member 1, a dash 2, a steering column 3, a steering wheel 4, a steam boiler 5 and a radiator 6.

The boiler 5 has disposed thereunder a burner 7 from which the flames 8 extend. Insulation 9 is disposed around the outer portion of the boiler 5 so as to prevent heat contained therein from radiating outwardly.

The exhaust fumes coming from the flames 8 will be normally carried through the tubes 41 contained in the boiler 5 into the chamber 10 in the upper part of the boiler 5 and thence out through the rear thereof as indicated by the arrows in Fig. 5. It oftentimes happens, however, that the burner 7 fails to function with the result that live gases will pass through the tubes 41 and gather in the chamber 10 and the tubes 41. Should the burner 7 then be ignited, an explosion is very likely to occur.

The forward portion of the chamber 10 is provided with a pair of doors 11 and 12 which are pivoted at 13 and 14 respectively so that they may swing inwardly and thus open the chamber 10 at its forward end.

The doors 11 and 12 are adapted to be opened and closed by pulling and pushing on the handle 15 of the rod 16 which latter rod is attached at its forward end to the bell crank 17 on one end of the pivot rod 14. A similar crank 18 is provided on the pivot pin 14 and attached to a rod 19 leading to a third crank 20 attached to the pivot pin 13.

I provide a fan 21 journalled on the shaft 22 and directly in the rear of the radiator 6. Also journalled on the shaft 22 is an electric motor 23.

In the operation of the fan 21 to be used as an aid in the condensation of water in the radiator 6, I have provided a battery 25 with the conductor 26 leading therefrom to a switch 27 located on the throttle rod

28 so that when the steam throttle rod handle 29 is moved so as to throw on the steam power, the switch 27 will likewise move and connect with the conductor 30 which leads to the electric motor 23 from whence the current passes through the conductor 31 back into the battery 25.

When it is desirable to clear out the gases which may have gathered in the chamber 10 by reason of the failure of the burner 7 to function, the operator pushes forwardly on the handle 15 of the rod 16 thus opening the doors 11 and 12 in the forward side of the chamber 10 and at the same time closing 15 an electrical connection leading from the battery 25 through the conductor 26 and the conductor 32 into the spring contact by reason of the contact therewith of the member 34 on the rod 16 which is constructed 20 of conducting material so that the current will flow on through the conductor 35 and the conductor 30 into the motor 23 and back through the conductor 31 into the battery 25 and starting the motor 23 and the fan 21. 25 It will thus be seen that the opening of the doors 11 and 12 and the simultaneous starting of the fan 21 will cause a current of air to flow through the chamber 10 as indicated by the arrows in Fig. 5, thus clearing 30 the same of any fumes which may be gathered therein and avoiding the possibility of an explosion.

Some changes may be made in the arrangement, combination and construction of 35 the various parts of my improved mechanism without departing from the spirit of my invention and it is my intention to cover by my claims such changes as may be reasonably included within the scope 40 thereof.

What I claim is:

1. In combination, a boiler having a burner thereunder for heating the same, a chamber adapted to receive gases from said burner, a normally closed entrance into said chamber and means for opening said entrance, a fan adjacent said entrance whereby when said entrance is opened and said fan is operated, gases within said chamber that have accumulated from the use of the 50 burner will be forced out.

2. In combination, a boiler having a burner thereunder for heating the same, a chamber, doors for said chamber and said doors adapted to be opened and closed by a rod extending therefrom, a fan adjacent thereto and adapted to force the gases within said chamber therefrom when said doors are opened.

3. In combination, a boiler having a 60 burner thereunder for heating the same, a chamber adapted to receive gases from said burner, a normally closed entrance into said chamber, a fan adjacent said entrance and means for simultaneously opening said entrance and starting said fan whereby gases formed in said chamber may be forced therefrom.

4. In combination, a boiler having a 70 burner thereunder for heating the same, a chamber adapted to receive gases from said burner, doors in said chamber adapted to be opened and closed by a rod extending therefrom, a fan adjacent thereto adapted to be operated by electrical power and means 75 whereby when said rod is moved to open said doors said fan will be started and force gases formed in said chamber therefrom.

ORR C. TRASK.
